GAS AND AIR CONTROL FOR GAS BURNERS

Roy E. Kamp, Fort Worth, Tex.

Application February 9, 1931, Serial No. 514,498

5 Claims. (Cl. 158—119)

This invention relates to gas burners and it has particular reference to gas and air control especially adapted to use in connection with gas burners in commercial plants for boilers, or 5 the like, and its principal object resides in the provision of a combination of elements calculated to regulate and control the introduction of fuel gas and air mixture so that an equal distribution of both elements will be permitted 10 to pass into the burner to increase the heating efficiency of the latter.

Another object of the invention resides in the provision of such an apparatus as will maintain, at all times, regardless of the desired pressure, a 15 proportionate mixture of gas and air, the streams of which being directed through the apparatus in such a manner as to become thoroughly mixed and commingled to produce a highly efficient fuel.

Still another object of the invention is manifest in the provision of an apparatus of the character described in which the operative elements therein can be adjusted with relation to each other so as to produce passages of greater 25 or lesser openings, as desired, with the minimum amount of effort.

Broadly, the invention seeks to comprehend the provision of a device which will completely control the introduction of fuel into a gas burner 30 in order that the greatest degree of efficiency may be realized in the use of such fuel.

While the foregoing objects are paramount, other and lesser objects will become manifest as the description proceeds taken in connection 35 with the appended drawing wherein:

Figure 1 is a side elevational view of the invention.

Figure 2 is a longitudinal sectional view of the invention, showing the operative elements there- 40 in and their relationship to each other.

Figure 3 is a plan view of the invention, and

Figure 4 is a cross sectional view taken on lines 4—4 of Figure 2.

In order to obtain the highest degree of efficiency by the use of gas as fuel, it is highly desirable to introduce a certain amount of air into the burner along with the gas and cause the same to be so thoroughly mixed and intermingled with the gas as to provide a more combustible 50 fuel and it is the primary object of the herein described invention to provide a means whereby such mixture can be accomplished.

Accordingly, the invention is provided with a body member or housing 1, one end of which is 55 open and is provided with an apertured flange

through which bolts, or similar articles can be inserted to secure the assembly in position, as shown in Figures 1 and 2. The opposite end of the housing 1 is closed, as exemplified particularly in Figure 2, and is integral with a sleeve, or cylindrical member or gas inlet chamber 3, the latter having an integral annular projection, or connection 4, shown in Figures 1 and 3, into which the gas inlet pipe is threaded.

A plunger rod 5 is operatively disposed longitudinally through the member 3, as shown in Figure 2, and is restrained from lateral movement within the member 3 by a guide member 6, the latter being threaded into the end of the member 3 and which is provided with a neck 10 portion 7, which arrangement is illustrated in Figure 2. Threaded upon one end of the plunger rod 5 is provided a substantially conical shaped control valve 8 which operates within an orifice 10 in the bottom of the gas chamber or member 3, previously referred to, and which will be more specifically described later. To prevent the escape of gas through the member 6 around the plunger rod 5 a packing gland is threaded into 20 the member 6.

As will be seen by reference to Figure 2, the upper end of the plunger rod 5 is rigidly affixed to a substantially U-shaped yoke 11.

Slidably arranged within the housing 1, as shown in Figure 2, a substantially conical shaped member 12 is provided, the purpose of which is to regulate the influx of air through the device and will be presently more definitely described. The member 12 is adjusted longitudinally within the housing 1 by means of rods 13 which are 30 threaded into the uppermost side of the member 12 and extend longitudinally therefrom, through apertures in the head 2 of the housing 1, their outer ends extending through the apertured ends of the yoke 11 and secured thereto by means of 35 lock nuts 14 and 15, as shown in Figures 1 and 2.

The housing 1 is provided with a series of elongated ports 16 arranged around the upper portion of housing 1 in the manner illustrated particularly in Figure 1, through which air can 45 pass through the device as illustrated by the arrows in Figure 2. An annular flange 17 is arranged around the lower end of the member 12 to slidably engage the inner walls of the housing 1 to prevent the passage of gas or air there- 50 through, as shown in Figure 2.

The lower end of the gas chamber 3 is also provided with a flange 18, the latter being beveled, as illustrated in Figure 2, to conform to the converging inner walls of the member 12 so 55

that uniformity in the annular opening 19 surrounding flange 18 between the latter and the inner walls of the member 12 can be maintained.

The primary object of the invention being to regulate and control the passage of gas and air into a conventional gas burner and maintain uniformity in the mixture of these elements, it is necessary that the respective passages of the air and gas be opened and closed simultaneously and proportionately with relation to each other.

In operation, therefore, when the yoke 11 is urged toward the housing 1 the plunger rod 5 is moved and, by reason of its connection to the latter, the conical valve 8 is displaced within the orifice 10. Due to the peculiar shape of the member 8, one end of which is smaller in diameter than its opposite end, its longitudinal movement through the orifice 10 will lessen or increase the surrounding passage within the latter as desired from time to time. By reason of the relationship between the yoke 11 and the member 12 through the rods 13, the member 12 is moved coordinately with the member 8, as illustrated in Figure 2.

In order to bring about the proper adjustment of the relationship of the passage 10 surrounding the member 8, and the passage 19 surrounding the flange 18, the lock nuts 14 and 15 can be moved along the rods 13, previously described.

The gas will pass into the chamber 3 through the lateral connection 4, as shown in Figure 1, and through the chamber 3, as indicated by the arrows in Figure 2, and out through the orifice 10 around the conical valve member 8 while, at the same time, air is drawn in by the passage of the gas through the apparatus through the open portions of the ports 16, which is also illustrated by the arrows in Figure 2. Obviously, when the yoke 11 is moved to or away from the housing 1 both passages 10 and 19 will be enlarged or reduced proportionately and, due to the oppositely inclined surfaces of the member 8 and the inner wall of the member 12, the air and gas streams will cross each other in the mixing chamber 20 thereby insuring a constant mixture of air and gas through the device at all times, capable of adjustment as desired.

Manifestly, the structure shown is capable of considerable modification and such modifications as are considered within the scope and meaning of the appended claims are also considered within the spirit and intent of the invention.

What is claimed is:

1. Air and gas control means for gas burners comprising an air chamber provided with air inlet openings and a gas chamber provided with a gas inlet and outlet, a substantially cone shaped gas control in said gas chamber diverging towards the said outlet and movable longitudinally therein to effect the passage of a diverging stream of gas therethrough a funnel shaped air control movable simultaneously with said gas control and surrounding said gas con-

trol and adapted to discharge a stream of air surrounding said stream of gas and at an angle thereto for cutting into the said stream of gas.

2. Air and gas control means for gas burners comprising an air chamber provided with openings for intake and discharge of air and a gas chamber provided with a gas inlet and outlet, a tapered gas control operating in the said gas chamber, a substantially conical air control member operatively disposed within the said air chamber, means for fixedly adjusting said controls relative to each other, means for fixedly adjusting said controls relative to the said inlet openings, the tapering surfaces of said controls serving to coordinate the feeding of gas and air and making the feed constant when once adjusted.

3. A gas and air control for gas burners comprising a housing having air inlet ports, a gas inlet chamber integral with the said housing, a gas outlet opening in one end of the said chamber, a substantially conical member operatively arranged within the said outlet, an air control member disposed within the said housing and movable relative to said air ports and the said end of the said chamber, the said substantially conical member and the said air control adjustably coordinating to control the air and gas mixture through the assembly.

4. In a fuel gas and air mixing device, an air chamber having ports therein, a cylindrical gas chamber having an inlet and outlet integral with the said air chamber, a slideable air control member longitudinally arranged within the said air chamber having guides secured thereto and projecting through apertures in the said air chamber, a yoke adjustably attached to the upper ends of the said guides, a substantially conical member concentrically arranged within the said gas outlet in the said gas chamber diverging toward the said outlet at one end and connected at its converging end to a guide rod, the latter extending longitudinally through the said gas chamber and fixed to the said yoke.

5. A fuel gas and air mixing device including an air chamber having ports arranged around the same, a gas inlet chamber arranged longitudinally and concentrically projecting into the said air chamber and integral therewith, a sliding air control member having flanges capable of engaging the inner walls of the said air chamber and being substantially funnel-shaped in its interior, a gas outlet in the said gas chamber communicating with the said air chamber, a flange surrounding the outlet end of the said gas chamber capable of adjustable relationship with the interior of the said air control, a substantially conical member concentrically arranged within the said gas outlet diverging outwardly into the said air chamber and converging into the said gas chamber, guide rods extending through apertures in the said air chamber and adjustably secured at their upper ends to a yoke, a plunger rod having one end threaded into the said conical member and fixed at its opposite end to the said yoke.

ROY E. KAMP.
